MASSACHUSETTS, ASSIGNEES, BY MESNE ASSIGNMENTS, TO COLUMBIA-
KNICKERBOCKER TRUST COMPANY, TRUSTEE, A CORPORATION OF NEW YORK.

APPARATUS FOR BURNING LIQUID FUEL.

1,103,617.

Specification of Letters Patent. Patented July 14, 1914.

Application filed December 29, 1909. Serial No. 534,205.

To all whom it may concern:

Be it known that we, WILLIAM E. OAKLEY, a citizen of the United States, residing at Millbury, in the county of Worcester and 5 Commonwealth of Massachusetts, and WILLIAM A. PENTECOST, a citizen of the United States, residing at Worcester, in said county and Commonwealth, have invented a new and useful Improvement in Apparatus for 10 Burning Liquid Fuel, of which the following is a specification accompanied by drawings, forming a part of the same; in which—

Figure 1 represents a side elevation of a steam boiler furnace equipped with our improved apparatus for burning liquid fuel, applied in the present instance for the purpose of heating the steam boiler. Fig. 2 is a side view on a larger scale, shown in section, of a portion of the apparatus for regulating 20 the flow of liquid fuel to the burner.

Similar reference characters refer to similar parts in the different figures.

Our present invention relates to that class 25 of apparatus for burning liquid fuel, in which are provided open pans in which the fuel is burned and over which currents of air pass carrying the flame and heated air wherever it is desired to apply the heat generated by the burning liquid fuel. In the 30 application of our apparatus the pans in which the fuel is supplied to feed the flames may be placed in proper position to conduct the currents of heated air through the flues of a boiler or into the heating chamber of a 35 furnace for melting metal.

The objects of our invention are to provide means for determining the heat generated by the burner; for controlling the combustion; and for increasing the efficiency of 40 the burner by controlling the relative supply of hydrocarbon and oxygen.

We accomplish the above objects by the construction and arrangement of parts as hereinafter described and pointed out in the 45 annexed claims.

Referring to the accompanying drawings 1 denotes the brick wall inclosing a steam boiler, not shown, and having a passage 2 for the admission of heated air and flames 50 from a fuel pan 4 in the direction of the arrows 5. The fuel pan 4 consists of a cast iron pan built into the end wall 6 of the steam boiler furnace and extending transversely across the front. The fuel pan 4,

shown in transverse sectional view in Fig. 55 1, is triangular in cross section, having its oblique sides 7, 7, inclosing a wide obtuse angle, preferably of 120° to 140°, in order that a slight variation in the depth of the liquid fuel may produce a relatively large 60 increase in the exposed surface of the fuel.

A recess or well 8 is preferably formed in the bottom of the pan into which is conducted a fuel supply pipe 9 leading from a fuel tank 10 which communicates by a pipe 11 with a second fuel tank 12, said tanks 10 and 12 being shown on a larger scale in sectional view in Fig. 2. The fuel tank 12 is supplied with liquid fuel, such as heavy mineral oil, through a supply pipe 13 which 65 leads from a source of fuel supply, such as an overhead tank, from which oil flows by gravity into the tank 12, and is controlled by a valve 14 which is automatically operated as hereinafter described.

The fuel tanks 10 and 12 are supported in the same horizontal plane as the fuel pan 4, so that the oil line in the two tanks and the fuel pan will stand upon the same level. Oil fed through the pipe 13 into the tank 80 12 will flow through the pipe 11 into the tank 10 and from the tank 10 through the pipe 9 into the fuel pan 4, the oil line being upon the same horizontal level in all three receptacles. The exposed surface 15 of the 85 oil in the fuel pan 4 is ignited, the hinged door 16 is opened to admit air to support combustion, and the heated air and flame pass in a current induced by the draft of a stack, not shown, through the passage 2 90 in the direction of the arrows 5. The products of combustion passing from the fuel pan 4 form a gaseous fuel which is still further mixed with air in the combustion chamber 17, a supply of air being admitted there- 95 to through the passage 18 by opening the hinged door 19. The heated current passing from the fuel pan 4 into the combustion chamber strikes against the opposing oblique wall 20 which serves as a baffle for the current and directs it downward toward the passage 2. The return or eddying movement of the current through the combustion chamber 17 facilitates the admixture of air entering through the passage 18, thereby se- 100 curing a more perfect combustion of the hydrocarbon carried from the fuel pan 4 and preventing the undue deposit of soot.

- It has been customary heretofore to control the passage of air across the surface of the liquid fuel and also to control the admission of air to the combustion chamber.
- 5 We secure an improved combustion, however, by a more intimate admixture of the oxygen and hydrocarbon in the current of gaseous fuel by means of the inclined wall 20, and we also secure a better combustion
- 10 by directing the flow of air over the liquid fuel in a downward direction, by means of a baffle-plate 21, which is placed above the fuel pan 4 and at an oblique angle to the horizontal plane of the fuel, so that air passing
- 15 over the fuel pan will be deflected downward as indicated by the arrow 22, and caused to impinge against the sheet of gaseous fuel produced from the burning fuel. We thus not only control the supply of oxygen and secure its intimate admixture with the gaseous fuel, but we further control the supply of hydrocarbon, which we accomplish by varying the exposed surface of the liquid fuel in the fuel pan 4.
- 20 In order to vary the relative proportions of oxygen and hydrocarbon it has been customary to vary the air supply, thereby increasing or decreasing the proportion of oxygen relatively to the supply of hydrocarbon in the current of gaseous fuel. While the method commonly practised may prove efficient under some conditions, we have found it to be of great advantage to place both the oxygen and hydrocarbon supplies
- 25 under immediate control either of the operator or automatically. In case the fuel supply is to be controlled by the operator it may be accomplished by the use of a hand valve 23 placed in the fuel supply pipe 9, which
- 30 may be so adjusted as to regulate the supply of oil relatively to its consumption so as to maintain a predetermined level in the fuel pan 4. A slight variation in the depth of the fuel in the pan 4 will produce a considerable variation in the area of its exposed surface owing to the wide angle inclosed between the oblique sides 7, 7, of the fuel pan. Under some conditions of use the control of the valve 23 by the operator may prove sufficient to regulate the hydrocarbon supply, but we provide an apparatus by which the depth of oil in the fuel pan 4 will be automatically regulated, the operation of the automatic apparatus being controlled by the quantity of heat developed by the burning fuel.
- 35 The quantity of heat developed may be indicated by any suitable apparatus by which heat may be translated into a mechanical movement, such for example, as a thermoelectric steam pressure diaphragm, or the like.
- 40 In the present instance we connect the boiler which is heated by the burning fuel through a steam pipe 24 with a casing 25, containing the usual steam pressure dia-
- 45 phragm, with a spindle 26 supported there-
- on and bearing against a lever 27 pivoted at 28 and coupled at its free end by a link 29 with the free end of a parallel lever 30 pivoted at 30. The levers 27 and 30 are provided with adjustable weights 31, 32 and 33, to counteract the lifting force of the spindle 26 as the latter is raised by the pressure of steam admitted to the casing 25 through the steam pipe 24. Pivoted to the lever 30 is a valve stem 34 which controls the flow of water under pressure through a pipe 35 into a piston equipped cylinder 36, carrying a piston stem 37 pivotally connected with a lever 38, which is pivoted at one end at 39, and also pivotally connected at 40 with a link 41 connected at its lower end with a plunger 42. Pivotally connected with the plunger 42 by a link 43 is a short arm 44 of a bell crank pivoted at 45 and having its long arm 46 connected by a link 47 with a sliding weight 48. The weight 48 is carried upon a beam 49 which is connected by a link 50 with a lever 51, pivoted at one end at 52 within the tank 12 and carrying upon its free end a float 53 in the tank 12. The beam 49 which carries the sliding weight 48 is pivoted at 54 upon a bracket 55, and the end of the beam 49 is connected by a link 56 with a lever 57, pivotally attached to a bracket 58 projecting from the casing of the valve 14. The lever 57 is provided with a stud 59 which works in a slot 60 of a sliding valve piston 61. As the lever 57 is raised by the upward movement of the beam 49 the valve piston 61 is pushed inwardly to close the passage through the supply pipe 13, and a downward movement of the lever 57 reverses the valve piston 61 and opens the supply pipe 13 to allow oil to flow into the tank 12.
- 55 The reciprocating movement of the lever 57 is caused by a reciprocation of the beam 49 on its pivot 54, which is produced by sliding the weight 48 to one side or the other of the pivot 54, which is accomplished by a swinging movement of the arms 44 and 46 of the bell crank. The bell crank is oscillated through its connection with the swinging lever 38 which is actuated by the rising and falling movement of the piston contained in the cylinder 36, as water under pressure is admitted above or below the piston by the movement of the valve stem 34. As the pressure of steam in the boiler raises the lever 27, the valve stem 34 is moved upwardly to admit water below the piston in the cylinder 36, which raises the free end of the lever 38. The upward movement of the lever 38 lifts the plunger 42 in the tank 10 and also slides the weight 48 on the beam 49 to the left of its pivot 54, thereby lifting the right hand end of the beam, partially closing the valve 14 and permitting the float 53 to rise. The flow of oil is thereby checked until the steam pressure is reduced, allowing
- 60 65 70 75 80 85 90 95 100 105 110 115 120 125 130

the weights on the lever 27 to depress the valve stem 34 to admit water above the piston in the cylinder 36, to depress the lever 38.

The downward movement of the lever 38 sinks the plunger 42 into the tank 10, and swings the bell crank to move the weight 48 to the right of the pivot 54 on the beam 49. The shifting of the weight 48 depresses the float 53 into the tank 12 and also moves the valve piston 61 to open the supply pipe 13 and admit an increased flow of oil to the tank 12. The effect of the depression of the plunger 42 and float 53 into the oil in the tanks 10 and 12 is to raise the oil line, not only in the tanks but also in the fuel pan 4. The raising of the oil line in the fuel pan 4 increases the area of oil surface exposed, consequently increasing the supply of hydrocarbon. To the free end of the lever 38, we connect the hinged doors 16 and 19 by chains 62 and 63, and an intermediate lever 64, having a series of holes for the attachment of said chains by which the movements of the doors 16 and 19 relatively to the lever 38 may be varied.

That part of the above described apparatus, comprising the casing 25, weighted levers 27 and 30, piston equipped cylinder 36 with the valve controlled water passages, 30 and lever 38, with connections to air draft closing devices, forms no part of our present invention, as it constitutes the well known "Spencer automatic damper regulator", the construction and operation of which will be well understood by those conversant with the control of steam boilers and furnaces.

The operation of our apparatus is as follows: Assuming the boiler to be cold, the free end of lever 38 will be depressed and the plunger 42 and float 53 in their lowest positions. Oil is admitted through the supply pipe 13 to the tanks 12 and 10, submerging the float 53 and the plunger 42, and flowing through the pipe 9 into the fuel pan 4, in which the oil line is raised substantially to the top of the pan. The hinged doors 16 and 19 being held open by the depressed end of the lever 38 allow free access of a sufficient body of air to the fuel pan and also to the combustion chamber 17 to support combustion, the maximum supply of hydrocarbon being furnished owing to the large area of oil surface exposed. The maximum amount of heat will be generated until steam pressure is produced sufficient to raise the lever 27 and connected valve stem 34, thereby admitting water below the piston in the cylinder 36, which raises the lever 38, and lifts the plunger 42 within the tank 10. As the plunger 42 is lifted the oil line immediately falls both in the tank 10 and also in the tank 12 and fuel pan 4. The fall of the oil line in the fuel pan decreases the area of exposed surface owing to the trian-

gular cross sectional shape of the pan, thereby decreasing the supply of hydrocarbon entering into the combustion of gaseous fuel. Any change, however, in reducing the steam pressure permits the weights 31, 32 and 33 to depress the valve stem 34 and admit water above the piston in the cylinder 36, and the lever 38 is again depressed, causing the doors 16 and 19 to be opened wider; the plunger 42 and float 53 to be lowered into the oil in the tanks 10 and 12 and the oil line raised in the fuel pan 4, at the same time opening the valve 14 and increasing the flow of oil through the supply pipe 13 to support the increased combustion, which continues until the steam pressure again reaches the desired point. The depression of the lever 38 also shifts the weight 48 to the right hand side of the pivot 54, and the weight 48, and falling float 53 operate to partially open the valve 14 of the oil supply pipe 13. Simultaneously with the movement of the lever 38 the hinged doors 16 and 19 are partially opened, thereby increasing the amount of oxygen supplied.

A slight adjustment of the weights 31, 32 and 33 and of the connection between the lever 38 and the hinged doors 16 and 19 will be sufficient to enable a complete control of both oxygen and hydrocarbon supplied to the gaseous fuel to maintain any desired pressure of steam.

By a control of the supply of hydrocarbon we obtain a clean hot flame without the formation of soot, which would clog the flue 100 passages, and coat the flue linings, thereby impeding the transmission of heat. We also further regulate the mixture of oxygen by an adjustment of the baffle-plate 21, which is accomplished by hinging the baffle-plate 105 21 at its inner edge at 64 and connecting its front by chains 66 with the lever 64. As the lever 64 drops in response to an increase in the steam pressure, the door 16 will descend and restrict the passage for the admission 110 of air and the baffle-plate 21 will likewise be lowered, carrying the diminished air current closer to the surface of liquid fuel in the pan 4.

We claim,

1. An apparatus for burning liquid fuel comprising a masonry structure having a front wall in which are located an open fuel pan and a supplementary air passage having a damper for opening and closing the 120 latter, and having formed back of said pan and supplementary air passage a combustion chamber, the inner wall of which opposite said pan and air passage is oblique, serving as a baffle and leading downwardly to a 125 passage for the admission of heated air and flame from the fuel pan.

2. In an apparatus of the class described, a fuel pan for liquid fuel, an air passage over said pan, means for controlling the quantity 130

of air admitted through said passage, and means for automatically varying the exposed surface of the liquid fuel in said pan in proportion to the quantity of air admitted through said passage.

3. In an apparatus of the class described, an open fuel pan triangular in cross section, a combustion chamber, an air passage over the top into said combustion chamber, means for controlling the supply of air to said passage, and means for simultaneously varying the supply of hydrocarbon to the air current, comprising means for automatically raising the fuel level in the fuel pan.

4. In an apparatus of the class described, an open fuel pan triangular in cross section, a fuel tank arranged on a level with the fuel pan, a pipe connecting said tank and fuel pan, a plunger inclosed in said tank, and means for raising and lowering said plunger to vary the fuel level in said fuel pan.

5. In an apparatus of the class described,

an open fuel pan, means for automatically varying the level of the fuel in said pan, a passage for an air current across the top of said pan, an adjustable baffle plate above said pan, and means for automatically varying the position of said baffle plate corresponding with the variation in the level of the fuel in said fuel pan.

6. In an apparatus of the class described, an open fuel pan, a passage for air across the top of said pan, a hinged door for controlling said passage and a hinged baffle plate above said pan, and means for simultaneously moving said door and said baffle plate.

Dated this seventeenth day of December 1909.
